ABSTRACT

A tube writing pen, including two writing tubes arranged coaxially one inside the other, the writing tubes communicating with an ink reservoir at their rear ends, and the inner writing tube being arranged for limited movement in and with respect to the outer writing tube, at least in the axial direction, a cleaning wire projects into the inner writing tube and a drop weight is attached to the cleaning wire at the end thereof adjacent the ink reservoir, the interior of the outer writing tube is widened frustoconically at its writing end, and the outer wall of the inner writing tube has a complementary frustoconically widened writing zone with a rounded end face.

FIG. 2

FIG. 1

TUBE WRITING PEN

This invention relates to a tube writing pen comprising two writing tubes arranged coaxially one inside the other which, at their rear ends, communicate with a reservoir for writing-ink or Indian-ink, and a cleaning wire which projects into the inner writing tube and which, at its rear end, is attached to a falling weight.

In one previously proposed tube writing pen, an inner tube writing point is designed to be axially displaced in an outer tube writing point against the pressure of a spring so that either the inner tube writing point or the outer tube writing point is effective, depending upon the pressure applied to the pen, in other words this tube writing pen can be used for drawing lines of different thickness, although the change in the thickness of the lines drawn is sudden rather than steady. In order to be able to draw or write with this previously proposed tube writing pen, the pen has to be held substantially vertical so that the front surface of the particular tube writing point rests on the writing surface. This previously proposed pen cannot be used for writing or drawing when held at an angle, as is usually the case with tube writing pens.

Various attempts have already been made to produce a writing instrument which does not use a nib in the usual sense, but instead has a writing point which is completely symmetrical so that with this writing instrument it is possible to write or draw at any angle of rotation about its longitudinal axis and, in particular, even at an oblique angle. One group of writing instruments of this kind uses an internally hollow writing point which tapers towards the front and which, towards its front end, has openings, whilst the actual point is closed. The laterally extending openings enable the pen to be used to some extent at an angle, although there are closed zones between the individual openings in the peripheral direction, as a result of which the line thickness at a constant oblique angle is not altogether independent of rotation of the writing instrument about its longitudinal axis because in one instance an opening may be in direct contact with the writing surface whilst, on another occasion, a closed zone between two openings may be in contact with the writing surface. Particular difficulties are encountered with these writing points in cases where it is desired to write or draw in an exactly vertical position because, in this case, the closed point is in contact with the writing surface and, especially where the writing surface is rigid, there is no connection to the openings.

Another difficulty of writing instruments of this kind is that the openings become clogged if the Indian-ink or writing-ink dries and, thereafter, the writing instrument can only be made to write again with considerable difficulty.

Since, in addition, these conventional writing points can only be produced with sufficient precision at considerable expense, they have not yet been accepted on a wide scale.

In another previously proposed writing instrument, the writing point is assembled by bending from lamellae joined together by means of webs so that the outer ends of the lamellae form the actual point.

In the case of this latter writing point, the actual point has to be welded or soldered because otherwise the lamellae would be bent upwards. Unfortunately, the welding or soldering operation is extremely difficult to

carry out in view both of the minuscule dimensions involved and of the precision required.

In another writing instrument for Indian-ink or writing-ink which is also said to write effectively at an angle, a central opening into which or from which projects a pin designed for displacement to a greater or lesser extent, if formed in the hollow writing point which tapers towards the front. Unfortunately, this writing instrument is attended by basically the same difficulties as other previously proposed writing instruments, because when the writing instrument is placed vertically on the writing surface so that it rests on the tip of the pin, writing is generally impossible whereas, when the pin is pressed in, the pen writes with the line thickness determined by the central opening. If the pin is not displaceable, it is not possible to write or draw with the pen held vertically and only to a very limited extent when the pen is held at an angle.

According to the present invention there is provided 20 a tube writing pen, comprising two writing tubes arranged coaxially one inside the other, the writing tubes communicating with an ink reservoir at their rear ends, and the inner writing tube being arranged for limited movement in and with respect to the outer writing tube, at least in the axial direction, a cleaning wire 25 which projects into the inner writing tube, and a drop weight which is attached to the cleaning wire at the end thereof adjacent the ink reservoir, the interior of the outer writing tube being widened frustoconically at its writing end, whilst the outer wall of the inner writing tube has a complementarily frustoconically widened writing zone with a rounded end face.

Thus, the present tube writing pen comprises two writing-ink or Indian-ink dispensing zones one of which 30 is formed by the central opening of the inner writing tube and the other of which is formed by the annular gap formed between the frustoconical front end of the outer writing tube and the correspondingly frustoconically widened front zone of the inner writing tube. Accordingly the present pen can be used in a vertical position in which it dispenses writing-ink or Indian-ink through the inner writing tube, whilst, in an inclined position, the writing fluid is generally dispensed through the inner writing tube and the annular gap 35 working in conjunction with one another.

Both the outer wall of the outer writing tube towards its front end and the front end face of the inner writing tube are preferably rounded off so that, for example, part of a sphere is formed and smooth, nonscratching writing or drawing is possible in every possible writing 40 position. In this embodiment, the frustoconical extension of the annular gap preferably extends perpendicularly of a tangent to the spherical surface in the vicinity of the annular gap.

Since the inner writing tube is designed for limited movement in the axial direction and, preferably, also for limited movement transversely of the longitudinal axis, it is displaced to some extent when the pen is placed on the writing surface so that, especially when the pen is held at an angle, whereby the size of the annular gap in the contact zone is varied in dependence upon the pressure applied so that pressure-sensitive writing is possible.

The inner writing tube can be displaceably mounted in the outer writing tube in a number of different ways. One very simple method of doing this is to widen the rear end of the inner writing tube so that it is able to

rest on a shoulder of the outer writing tube which forms a rear contact surface.

In order to enable the invention to be more readily understood, reference will now be made to the accompanying drawings, which illustrate diagrammatically and by way of example an embodiment thereof, and in which:

FIG. 1 is a side elevation of a tube writing point for a tube writing pen, and

FIG. 2 is a diagrammatic section through part of the front zone of the tube writing point shown in FIG. 1.

The tube writing point shown in FIG. 1 consists of an outer body comprising an inner compartment which communicates with a reservoir for writing-ink or Indian-ink and in which a drop weight 4 is arranged. This drop weight is designed for movement at least in the axial direction of the tube writing point and, at its front end, carries a cleaning wire 3 (FIG. 2) which projects into an inner writing tube 1. The drop weight is prevented from dropping out in conventional manner by means of a clip 6.

In addition, a compensating chamber 5 is formed on the outer surface of the outer body and extends in the vicinity of a thread for fixing the writing point in place, the compensating chamber communicating at its upper end with the ink reservoir or the inner compartment and, at its lower end, with the surrounding atmosphere. The mode of operation and function of a compensating chamber of this kind are known.

A fixed outer writing tube 2 is inserted into the front end of a casing of the writing point and the inner writing tube 1 is arranged coaxially in the outer writing tube 2. Both writing tubes 1 and 2 communicate at their rear ends with the ink reservoir.

As can be seen from FIG. 2, the interior of the outer writing tube 2 is widened frustoconically at its front end 8, whilst the front zone 7 of the inner writing tube 1 is correspondingly frustoconical so that an annular gap is formed in this zone between the inner and outer writing tubes, this annular gap 11 communicating with the ink reservoir through the annular gap between the inner and outer writing tubes.

As can readily be seen from FIG. 2, the inner writing tube 1 can only move rearwards to a limited extent in the axial direction of the tube writing point because the frustoconical widenings come into contact with one another in the front zones. The axial movement of the inner writing tube 1 towards the front is limited by a widening 10 provided at the rear end which comes into contact with a shoulder-like widening 9 of the outer writing tube 2. Assembly of the inner writing tube is readily carried out by inserting the inner writing tube which, initially, is not widened at its rear end into the outer writing tube 2, and then widening its rear end.

The outer wall, in the vicinity of the front end 8 of the outer writing tube, and the end wall of the inner writing tube 1, in the zone 7, are rounded off with substantially the same radius of curvature in such a way that they form part of a sphere. This partial sphere is particularly suitable for use as the writing point because the parts of the sphere can be moved smoothly without scratching over a writing surface.

If the tube writing point is used for writing or drawing in a vertical position, the writing-ink or Indian-ink flows to the point solely through the central bore in the inner writing tube 1, and the pen works in the same way as a conventional tube writing pen. In addition, in this

position, the inner writing tube is moved axially to the rear so that, on the one hand, the widened zone 10 moves out of contact with the surface 9 so that writing-ink or Indian-ink is able to flow into the annular gap between the inner and outer writing tubes, whilst on the other hand particles of writing-ink or Indian-ink which have dried in the aforementioned annular gap are released by the movement of the inner writing tube, ensuring the flow of writing fluid to the annular gap 11.

If the pen is used at an angle, the zone between the longitudinal axis and the annular gap generally comes into contact with the writing surface which, in the case of a non-rigid surface, means that writing fluid flows onto the writing surface both from the annular gap and also from the central bore. The size of the annular gap in the dispensing zone is influenced by the pressure applied to the inner writing tube which is able to move both in the axial direction and also to a limited extent transversely of the longitudinal axis, in other words the flow of writing-ink or Indian-ink through the annular gap is governed by the pressure applied.

The present tube writing pen is even able to write in cases where the inclination is increased to such an extent that the pen is only in contact with the writing surface in the vicinity of the annular gap so that no writing-ink or Indian-ink is available from the central bore in the inner writing tube. In this case, too, the line thickness is governed by the intensity of the pressure applied.

Thus, the present pen represents a writing instrument which can be used both in a vertical position and also at an angle, despite rotation about its longitudinal axis, and allows pressure-sensitive writing or drawing, as would otherwise only be possible with a pen holder.

I claim:

1. A tube writing pen comprising:
  - A. an outer writing tube;
  - B. an inner writing tube coaxially spacedly positioned within said outer writing tube and forming therebetween an annular gap;
  - C. an ink reservoir in communication with both said tubes at the rear ends thereof and the annular gap therebetween;
  - D. said inner writing tube being mounted for limited relative movement in an axial direction and limited movement transversely of the longitudinal axis within said outer writing tube;
  - E. a cleaning wire projecting into said inner writing tube and having a drop weight attached at the end proximate said ink reservoir;
  - F. said outer writing tube having a bore frustoconically widened at the writing end thereof;
  - G. said inner writing tube having the wall thereof frustoconically widened at the writing end thereof correspondingly and complementarily to the frustoconical widened end of said outer writing tube and forming an annular gap therebetween for an ink flow passage constituting a writing zone;
  - H. said inner and outer writing tubes terminating at the writing ends thereof in rounded end faces having rounded edges and which rounded end faces have substantially the same radius of curvature and complementarily constitute portions of sphere and conjointly form a smooth rounded writing surface

- face for varied angular writing positions of said pen;
- I. the frustoconical surfaces of the inner and outer writing tubes each extending perpendicularly of a tangent to the rounded writing face and terminating in the writing surface face of the sphere;
- J. limited axial and transverse movements and resultant displacement of said inner writing tube in said outer tube when said pen is placed on a writing surface and disposed at an angle thereto varying the size of said annular gap in the contact zone in dependence upon pressure applied for pressure-

- sensitive writing control and said rounded edges precluding erratic and scratchy writing; and
- K. the ends of said inner and outer writing tubes proximate said ink reservoir having complementarily frustoconically widened inner end portions, axial movement of said inner tube with respect to said outer tube being limited in a forward direction by coaction of said widened inner end portions, and in reverse direction by coaction of said frustoconically widened writing ends of said tubes.
